UNITED STATES PATENT OFFICE.

OLIVE K. WOOLLEN, OF FRANKLIN, INDIANA.

INVALID'S BED.

No. 874,555.

Specification of Letters Patent.

Patented Dec. 24, 1907.

Application filed August 19, 1907. Serial No. 389,199.

To all whom it may concern:

Be it known that I, OLIVE K. WOOLLEN, a citizen of the United States, residing at Franklin, in the county of Johnson and State 5 of Indiana, have invented certain new and useful Improvements in Invalids' Beds, of which the following is a specification.

This invention relates to beds for invalids; and the object of the invention is to provide 10 a bed of the above character which is capable of being swung so as to change the position of the patients without disturbing them.

A further object of the invention is to provide an invalid's bed with a central aperture 15 which is normally closed by a movably mounted stand which may be raised or lowered by means of a screw shaft in order that the patients may be provided and have access to the necessary vessels without subjecting 20 the patients to unnecessary handling or shifting.

A further object of the invention is to provide an invalid's bed which is arranged so that the head or feet of the patients may be 25 raised into an inclining position.

I accomplish the objects of my invention by means of a bed illustrated in the accompanying drawings, forming a part hereof, in which—

30 Figure 1 is a top or plan view of an invalid's bed embodying my said invention, in which a portion of the mattress is broken away to disclose the parts underneath. Fig. 2 is a side elevation of the construction 35 shown in Fig. 1, except that the mattress has been omitted. Fig. 3 is a rear elevation of the bed. Fig. 4 is a central vertical sectional view of a portion of the bed showing the movable stand or table occupying its normal 40 position. Fig. 5 is a perspective detail.

In the drawings, 1 represents the head and 2 the foot of the bed, each of which rest upon the bases 4 and 5. The bases are held in normal relation with one another by means of a 45 plurality of connecting bars 6.

The bed proper consists of a rectangular frame comprising the end rails 7 and 8 which are secured at each end by the side rails 10, the latter being secured to the end rails by 50 means of any suitable fastening employed in the art of bed construction. The end rails 7 and 8, and the side rails 10 support an inner frame which carries the woven wire springs. This inner frame is divided into the forward 55 member 13 and the rear member 14 which are hingedly secured to the stationary mem-

bers 12 of the frame by means of the hinges 16. This arrangement admits of these end members being raised into an incline position, as shown in Fig. 2. The members 13 60 and 14 are held in elevated position by means of the braces 17 which are pivotally secured to said members and engage notches 18 in the side rails 10. The members 13 and 14 of the inner frame are notched at 20 so 65 that the braces 17 may be nested when said members are in their reclining or normal position. To add an additional support and thus prevent the woven wire springs from sagging, I provide the coil-springs 25 which 70 bear against the under side of the woven wire springs while the lower ends of said springs are mounted upon the rails 26 which are supported by the side rails 10. The bed is also provided with the usual mattress 28 75 which lies upon the woven wire springs and is held in position by means of the hooks 29, which are common to folding beds. The woven wire springs and the mattress 28 are each provided with a central registering 80 aperture 30. This aperture is normally closed by means of the cushion 31 which is formed of similar material as the mattress 28. The cushion 31 is mounted on the springs 34 so that it will move with the mattress 28 when the weight of the patient is thereon. The springs 34 are mounted on the base-plate 35, which base-plate rests on the head-plate 36, the latter being secured to the vertical screw shaft 37. The shaft 37 90 passes through the screw threaded collar 38, and by means of the hand wheel 39, the head-plate 36 together with the cushion 31 may be raised or lowered. The base-plate 35, carrying the cushion 31, is prevented from 95 moving laterally off of the head-plate 36 by means of the hook-shaped springs 42 which are secured at diametrically opposite sides of the head-plate 36 and are susceptible of being bent away from said head-plate and 100 thus permitting the base 35 to be removed. The screw-shaft 37 is moved into its extreme lower position when it is desired to remove the cushion 31 and substitute the vessel which is intended for the patient's use. The 105 collar 38 is secured to the floor 45 which is suspended from the bottom of the bed by means of the uprights or hangers 46.

The bed proper may be swung so as to be able to change the position of the patient by 110 attaching to the under side of the end rails 7 and 8 the semi-circularly formed supports

50, which rest and support the bed at all time upon the extended portions of the bases 4 and 5. The frame of the bed is swung from the center pivots 51 which pass through 5 both the head 1 and foot 2. To enable the bed to be easily manipulated I provide the vertically extending parallel bars 55 and 56. The bar 55 passes downward on the rear side of the head 1 of the bed and is connected 10 with the rocker 50 by means of the bolt 58. A sleeve 60 surrounds the bolt 58 and extends from the bar 55 to the rocker 50 so as to compensate for the thickness of the posts of the head 1. The bars are secured together at their top ends by means of the bolt 62. In order to securely hold the bed when tilted into an angle I provide the clamping bolt 65 which passes through both the bars 15 55 and 56 and through a slot 66 in the tie rail 55 and 67 of the head 1. The slot 66 is cut on an arc which is concentric with the pivot bolt 51, and the vertical bars 55 and 56 are clamped tightly against the surfaces of the tie rail 67 by means of the hand wheel 70 20 mounted on the threaded end of the clamping bolt 65. The hand wheel 70 is preferably placed on the back side of the head 1 of the bed, where it will be easily accessible and still be hidden from view. As an additional 25 security for holding the bed when it occupies its normal vertical position I may provide the pin 72 (see Fig. 3) which will pass through one of the tie rails of the head 1 and into the end rail 7 of the bed. This pin is 30 not deemed absolutely necessary, but may be added if desired.

Having thus fully described my said invention, what I desire to secure by Letters Patent, is—

40 1. An invalid's bed comprising a head and foot member secured together and each of said members being provided with a projecting base, a bed-frame arranged between the head and foot members, means for pivotally 45 mounting said bed-frame between the head and foot members, semi-circularly formed supports secured to the underside of the bed-frame and adapted to ride upon the projecting portions of the bases, means for changing 50 the position of the bed-frame, and means for locking the bed-frame in the desired position.

55 2. An invalid's bed comprising a head and foot member secured together, each of said members being provided with a projecting base, a bed-frame arranged between the head and foot members, means for pivotally mounting said bed-frame between the head and foot members, semi-circularly formed supports secured to the underside of 60 the bed-frame and adapted to ride upon the

projecting portions of the bases, means for changing the position of the bed-frame, a woven-wire spring supporting frame comprising a plurality of sections in which the middle sections are adapted to normally lie 65 in a horizontal position while the end sections are susceptible of being moved into an inclined position, means for hingedly securing the end sections to the middle sections, means for holding the end sections when 70 raised, and means for locking said bed-frame in a desired position.

3. An invalid's bed comprising a head and foot member secured together, each member being provided with a projecting base, a bed-frame arranged between the head and foot members, means for pivotally mounting said bed-frame between the head and foot members, semi-circularly formed supports secured to the underside of the bed-frame and 75 adapted to ride upon the projecting portions of the bases, means for changing the position of the bed-frame, a woven-wire spring provided with a centrally located aperture and its supporting frame comprising a 80 plurality of sections in which the middle sections are adapted to normally lie in a horizontal position while the end sections are susceptible of being moved into an inclined position, means for hingedly securing the end 85 sections to the middle sections, means for holding said end sections when raised, a head-plate adapted to register with the central aperture in the woven-wire springs, means for changing the position of said head-plate, and means for locking said bed-frame 90 in a desired position.

4. An invalid's bed comprising a head and foot member, each of said members being provided with a projecting base, a bed-frame 100 arranged between the head and foot members, means for pivotally mounting said frame between the head and foot members, semi-circularly formed supports secured to the underside of the bed-frame and adapted 105 to ride upon the projecting portions of the bases, a plurality of uprights secured to and adapted to move with the bed-frame, said uprights straddling the head member, and a clamping device passing through the uprights and the head member, for locking the bed-frame in the desired position.

In witness whereof, I, have hereunto set my hand and seal at Indianapolis, Indiana, this 14th day of August, A. D. one thousand 115 nine hundred and seven.

OLIVE K. WOOLLEN. [L. S.]
